(57) **CLAIM**

The ornamental design for handling apparatus as shown and described.

DESCRIPTION

2. Handling apparatus

2.1) Back view of an ornamental design for a handling apparatus;

2.2) Front right perspective view of the handling apparatus of FIG. 2.1;

2.3) Front view of the handling apparatus of FIG. 2.1;

2.4) Top plan view of the handling apparatus of FIG. 2.1;

2.5) Front left perspective view of the handling apparatus of FIG. 2.1;

2.6) Right side view of the handling apparatus of FIG. 2.1;

2.7) Left view of the handling apparatus of FIG. 2.1;

2.8) Rear right perspective view of the handling apparatus of FIG. 2.1;

2.9) Rear left perspective view of the handling apparatus of FIG. 2.1;
